ATTORNEY

UNITED STATES PATENT OFFICE.

HARRY B. HILLS, OF LOS ANGELES, CALIFORNIA.

BRAKE BAND.

Application filed December 6, 1926. Serial No. 152,782.

My invention relates to brake bands, which are generally used in connection with a rotating drum to which a load is applied, for the purpose of restraining or stopping the rotation of the drum and thereby the movement of the load. The object of the invention is to provide a tri-member band so acting as to have a snubbing action on the drum, in combination with means whereby the release of the brake band may be quickened and the releasing movement of one member of the band may be directly communicated to an adjacent member. Other objects will hereinafter appear.

15 In the accompanying drawings—

Fig. 1, is a view partly in vertical section and side elevation of a rotating drum to which a load is applied, and a brake band embodying my invention.

20 Fig. 2, is an end elevation partly in vertical section of the device shown in Fig. 1.

Figs. 3 and 4 are detail views of portions of the brake band shown in Figs. 1 and 2.

25 Fig. 5 is an end elevation showing a modified form of brake band and embodying my invention.

Similar reference characters designate corresponding parts in all of the figures.

1 designates a rotating brake drum, which 30 may form a part of any type of mechanism to which a load is attached or connected. For example it may be comprised in a windlass or any other type of hoisting and lowering mechanisms, or it may be comprised in a vehicle which is to be stopped by means of a brake band. In the drawings the drum is shown as being mounted on roller or other anti-friction bearings in standards 2, only one of which is shown, and as being rotated 35 in the direction of the arrow α under the influence of a load. In this direction the rotation of the drum is controlled by the brake-band. The opposite direction of rotation of the drum is shown as being secured through 40 the shaft 3 to which the drum is secured. The end 4 of the shaft 3 is squared to receive a crank. In this direction of rotation the shaft rotates free of the brake band.

45 My improved brake-band consists of a strap of metal which is wound around the braking surface of the brake drum. One end of the strap is fixed, while the other end is moved under control to regulate the frictional engagement of the convolutions of the 50 strap with the braking surface of the drum.

The brake band, shown in Figs. 1 to 4 com-

prises a single strap 5^a which extends around the drum for nearly its entire circumference and two other straps 5^b, 5^c which also extend around the drum for nearly its entire circumference and outside of the single strap 5^a as shown in Fig. 2. The adjacent ends of the single strap 5^a and straps 5^b, 5^c are connected or coupled together by a suitable coupling or connection as shown in Fig. 3. Any desired form of coupling or connection may be used. As here shown it comprises a plate 6^a riveted to the single strap 5^a and a plate 6^b riveted to the two straps 5^b, 5^c. Both plates 6^a, 6^b have a flange 6^c through which a bolt 6^d passes. 70 The other end of the single strap 5^a has riveted to it a plate 7^a which is fastened to a cross piece 7 comprised in the frame work, while the other ends of the straps 5^b, 5^c have riveted to them a plate 7^b (Fig. 4) secured to a crank arm 75 8 (see Figs. 1 and 2) fixed upon a shaft 9, suitably journaled in boxes 10 which are shown as being bolted to the cross-piece 7. One end of a controlling lever 11 is also fixed to the shaft 9, the other end of which is provided 80 with a handle 11^a. A weight 12 is also provided on the lever 11 the function of which is to normally hold the brake band onto the drum to prevent it from rotating. This pressure may be increased beyond that offered by 85 the weight by depressing the lever 11. The brake band is released from the drum so as to leave it free to rotate by raising the lever 11. If desired, in the form shown in Figs. 1 to 4 the releasing of the brake band may be quickened by any desired means which act upon the lifting of the lever to release the straps 5^b, 5^c and subsequently and in turn the single strap 5^a. As here shown these means comprise a rod 15 connected at one end with the crank 90 arm 8, and engaging the plate 6^a with its other end. When lever 11 is raised crank arm 8 is swung to the left from its position in Fig. 1, the straps 5^b, 5^c are moved in releasing or slack position, the actuation beginning at the outer 95 ends thereof. Simultaneously therewith rod 15 acts to release the intermediate portion of the brake band viz, at that point where the inner ends of straps 5^b, 5^c join strap 5^a, and to further insure quick and uniform releasing 100 action the inner strap 5^a carries clips 5^a overhanging the outer straps 5^b, 5^c and compelling the latter to impart their releasing movements to the former. Also the outer straps 105 carry clips 5^d overhanging the inner strap so 110 that releasing movements of the latter are communicated to the former.

In order that the releasing movement of plate 7^b will not bow the straps 5^b, 5^c at the ends thereof but will distribute the slackness about the circumference of the brake drum, I 5 form the plate with projecting legs 5^e each secured to one of the said spaced straps, serving to reinforce and so stiffen them that the difficulty is obviated.

In Fig. 5 the brake band is shown as being 10 a single strap 20, wound about the braking surface of the drum, one end 20^a of the strap is secured to the frame-work as is the single strap 5^a in Fig. 1, and the other end 20^b is secured to a crank arm as are the two straps 15 5^b, 5^c in Fig. 1, for the same purpose.

It will be observed that the form of brake band shown in Fig. 1 is, structurally, the equivalent of the form of brake band shown in Fig. 5 in so far as the brake band is a single 20 strap. The effect is precisely the same.

Having described my invention, what I claim and desire to secure by Letters Patent is as follows:

In brake mechanism, a brake drum, a brake band on said drum and being of a length to 25 wrap around the same a plurality of times, said band comprising two spaced straps and an intermediate strap connected thereto, means for contracting the band about the drum and for releasing the same, clips carried by the intermediate strap and overhanging the spaced straps and clips carried by the spaced straps and overhanging the intermediate straps, the clips being adapted to mutually 30 coact and transmit the releasing movements 35 of any one of the straps to the other straps.

In testimony whereof I have signed my name to this specification.

HARRY B. HILLS.
